UNITED STATES PATENT OFFICE.

WARREN V. EATON, OF KANSAS CITY, MISSOURI.

GARMENT-COLLAR.

No. 872,914.

Specification of Letters Patent.

Patented Dec. 3, 1907.

Application filed March 23, 1906. Serial No. 307,706.

To all whom it may concern:

Be it known that I, WARREN V. EATON, a citizen of the United States, residing at Kansas City, in the county of Jackson and State 5 of Missouri, have invented certain new and useful Improvements in Garment-Collars, of which the following is a specification.

My invention relates to garments, and more especially to those worn in the cold and 10 stormy seasons of the year, such as are made of flannel, corduroy and analogous materials, and my object is to produce a garment provided with a collar which can be worn as a turn-down collar or can be used as a standing 15 collar or muffler to protect the throat in cold and wet weather.

A further object is to produce a garment having a collar of the character mentioned which when turned down presents the same 20 appearance as an ordinary turn down collar and which when turned up presents an attractive appearance to the eye.

A still further object is to produce a convertible collar of the character outlined 25 which can be easily, quickly and cheaply made.

With these objects in view and others as hereinafter appear, the invention consists in certain novel and peculiar features of construction and organization as hereinafter described and claimed; and in order that it may be fully understood reference is to be had to the accompanying drawing, in which—

Figure 1, is a perspective view of a portion 35 of a shirt provided with a collar embodying my invention, the collar being shown as turned down. Fig. 2, is a similar view with the collar secured in its upstanding position. Fig. 3, is a view of the collar and shirt open. 40 Fig. 4, is a perspective view of a portion of a shirt provided with a collar of slightly modified form. Fig. 5, is a view with a shirt and collar of the type shown in Fig. 4, stretched open.

45 In the said drawing 1 indicates a shirt of any suitable material, and 2 the collar, said collar comprising the neck-band portion 3, and the body portion 4 turned down over the neck-band portion so as to present to view a 50 collar of ordinary appearance. The neck-band portion is provided with button holes 5 and 6, for the reception of an ordinary collar button 7, and at one end the collar is provided with an extension tab 8, to lap over the 55 other end of the neck band, said tab having a button hole 9 for engagement with an ordinary

button 10, stitched to said overlapped portion of the neck-band. The collar as thus far described is common in flannel and like shirts.

60

Stitched or otherwise secured to the under or outer side of the turned down portion of the overlapped end of the collar is a pair of buttons 11, and projecting from the opposite end of the same portion is a tab 12, provided 65 with a pair of button holes 13, which normally engage with a pair of buttons 14 stitched or otherwise secured to the outer or under side of the same portion of the collar, said tab 12 not being discernible when its button holes 70 engage the buttons 14, with the body portion of the collar turned down.

When desired the turned down portion of the collar can be raised and secured in such 75 position by unbuttoning tab 12 from the buttons 14 and turning it back so as to cause it to overlap the opposite end of the collar, in which position it is buttoned upon the buttons 11, the collar then appearing as shown in Fig. 2, and presenting an attractive appearance with the buttons 11 and 14 disposed at opposite sides of and equal distances from the center of the collar.

In Figs. 4 and 5 I show a collar of the same 80 general character except that each of its ends is provided with a tab to overlap and button upon the opposite end instead of having the tab upon one end only. In said figures, 15 indicates the lower tab and 16 the upper tab at opposite ends of the body portion of the 85 collar, and said tabs are provided with button holes 17 so that the tab 15 can be buttoned back upon button 18 and the tab 16 on the button 19 when the collar is turned down, at which time it presents the appearance 90 shown in Fig. 1. When the collar is turned up as a muffler or protector for the throat, the tabs 15 and 16 are unbuttoned from their respective buttons and are caused to overlap the contiguous ends and button 95 20 and 21 respectively upon the buttons 20 and 21.

It will be apparent that other methods of fastening may be employed in lieu of the buttons and button holes without departing from the principle of construction involved, and that, as various modifications may be made in the form, proportion, detail construction and arrangement of the parts, I do not wish to be restricted to the exact construction shown and described.

105

I am aware that prior to my invention over-coat collars have been made large enough to

110

be turned up around the neck and face of the wearer but I make no claim to such arrangement.

I am also aware that the waist-bands of 5 undergarments have been adjusted by means of straps extending across the division in the waistband and fastened to the waistband but such device also is foreign to my invention.

Having thus described the invention what 10 I claim as new and desire to secure by Letters Patent, is:—

As a new article of manufacture, a garment-collar consisting of a neck-band portion having fastening means at its ends, and 15 a body portion secured to the upper edge of

the neck-band portion and provided at its end with a longitudinal extension adapted to be folded under and hidden by the body portion or extended across to overlap the opposite end of the body portion, the body portion being further provided at its ends with permanent fastening means to hold the longitudinal extension in its folded under or its extended over position. 20

In testimony whereof I affix my signature, 25 in the presence of two witnesses.

WARREN V. EATON.
